INVENTOR
ROBERT N. MURPHY

BY Peterborough ^{1716.}

UNITED STATES PATENT OFFICE.

ROBERT NICHOLAS MURPHY, OF OTTAWA, ONTARIO, CANADA.

HEATING SYSTEM.

1,409,231.

Specification of Letters Patent. Patented Mar. 14, 1922.

Application filed February 17, 1919. Serial No. 277,565.

To all whom it may concern:

Be it known that I, ROBERT NICHOLAS MURPHY, a subject of the King of Great Britain, and resident of the city of Ottawa, 5 in the Province of Ontario, Dominion of Canada, have invented certain new and useful Improvements in Heating Systems, of which the following is a specification.

This invention relates to improvements in 10 heating systems, and the general object of the invention is to obtain greater efficiency in the conversion of combustible fuel into heat, and in the distribution of the latter.

The invention may be applied in a great 15 variety of forms, one of the principal features common to all forms is the embedding of means, through which the heat distributing fluids are circulated, in the fuel bed.

Further objects are to permit of various 20 kinds of fuel, such as soft or hard coal, lignite, garbage, wood, oil and the like being used, and to permit of several sections of the heater being readily accessible for removal and repair.

25 Further objects still are to transmit a greater degree of heat to the smallest volume of circulating fluid, by placing the circulating means in direct contact with the burning fuel, and generally to adapt the 30 several parts to better perform the functions required of them.

With the above and other objects in view the invention consists essentially of the improved construction hereinafter described 35 and set forth in the following specification and accompanying drawings forming part of the same.

In the drawings:

Figure 1 is a sectional elevation of a water 40 heater embodying my invention.

Figure 2 is a fragmentary sectional elevation of part of the fluid circulating element.

Figure 3 is a transverse section through 45 the upper portion or header of the fluid circulating element.

Like characters of reference refer to like parts in the several figures.

Referring now to the drawing the fluid 50 circulating element comprises a header 28 formed with a baffle wall 29 therein, which divides the header into two chambers 30 and 31, with the former of which the inlet water pipe 32 communicates, and with the latter the outlet water pipe 33.

55 The lower end of the header is provided with a plurality of orifices 34 in which the

upper open end of tubes 35 extend, and these tubes are designed to project downwardly into the fuel in the heater.

Each of the tubes 35 is provided with a 60 baffle wall 36 having an orifice 37 adjacent to the lower end, thereby forming a U-shaped passageway through which the fluid circulates.

The upper end of the baffle wall 36 en- 65 gages with the lateral wall of the baffle 29 in the header. The header 28 is formed annular, with a concentric orifice provided with a damper 38 which is operable externally of the heater by means of the spin- 70 dle 29.

A combustion chamber 40 is formed be- 75 tween the outer periphery of the tubes 35 and the inner wall of the body portion 10, and into this combustion chamber a down- wardly extending pipe 41 extends to supply pre-heated air to the fuel on the grate.

When the type of my invention particu- 80 larly illustrated in the drawing is in use the damper 38 is opened and fuel fed through the doorway 13 and down through the central passageway of the header 28 and be- 85 tween the tubes 35, so that the fuel will form a conical heap on the grate and build up around the lower portion of the tubes.

The damper 38 is then closed and the 90 products of combustion pass through be- 95 tween the tubes 35 into the combustion cham- ber 40, where the gases intermix with the pre-heated air delivered through the pipe 41, so that an after burning of these gases takes place, completing the combustion of the same, and the products of combustion after travelling around the outer wall of the header 28 are ultimately discharged through the smoke stack 14.

In this case also the doorways 15 may be opened to supply further air to the fire, if such is necessary, and the pipe 41 may be duplicated if a larger supply of hot air is 100 necessary for the well working of the heater.

As many changes could be made in the above construction, and many apparently widely different embodiments of my invention, within the scope of the claim, con- 105 structed without departing from the spirit or scope thereof, it is intended that all matter contained in the accompanying specifi- cation and drawings, shall be interpreted as illustrative and not in a limiting sense. 110

What I claim as my invention is:

In a heater, a fluid circulating element

comprising an annular header, having a central feed, tubes depending from the header, a baffle wall in each tube having an orifice in the lower end forming the tube into a U-shaped passageway, the upper end of the baffle wall extending into the header, a baffle wall in the header subdividing it into two consecutive compartments and abutting the projecting portions of each of the said baffle walls, the lower edge of the last said baffle extending diametrically across the upper ends of all the tubes, an inlet pipe extending through the header and last said baffle wall

into the inner compartment of the header, an outlet pipe extending from the outer compartment of the header and located diametrically opposite the inlet pipe, a damper pivotally mounted in the central opening of the header and means for actuating the damper externally of the header. 20

In witness whereof I have hereunto set my hand in the presence of two witnesses.

ROBERT NICHOLAS MURPHY.
